(57) **CLAIM**

The ornamental design for a pinny clip, as shown and described.

DESCRIPTION

FIG. 1 is an elevational front view of a pinny clip according to the present invention;

FIG. 2 is an elevational rear view thereof;

FIG. 3 is an elevational left side view thereof;

FIG. 4 is an elevational right side view thereof;

FIG. 5 is a plan top view thereof; and,

FIG. 6 is a plan bottom view thereof.

The broken lines showing in the figures are included for the purpose of illustrating environment of the design and form no part of the claimed invention.
